UNITED STATES PATENT OFFICE.

CLYDE ERSKINE, OF CHICAGO, ILLINOIS, ASSIGNOR TO HARRIE H. WALSH, OF CHICAGO, ILLINOIS.

ADVERTISING PROJECTING DEVICE.

1,290,947.

Specification of Letters Patent. Patented Jan. 14, 1919.

Application filed August 21, 1916. Serial No. 115,921.

To all whom it may concern:

Be it known that I, CLYDE ERSKINE, a citizen of the United States, and a resident of Chicago, in the county of Cook and State 5 of Illinois, have invented certain new and useful Improvements in Advertising Projecting Devices; and I do hereby declare that the following is a full, clear, and exact description thereof, reference being had to 10 the accompanying drawings, and to the letters of reference marked thereon, which form a part of this specification.

This invention relates to improvements in advertising projecting devices and consists of the matters hereinafter described and more particularly pointed out in the appended claims.

One of the objects of the invention is to provide an advertising device more especially intended for window display which will immediately attract and hold the attention of the passersby to the matter advertised by reason of the unique manner in which it is presented. To this end the device is constructed and arranged to throw upon a dark screen, which forms part of the device, illuminated characters, letters or devices forming words, sentences and the like, part of which are stationary and part of which 30 move in an endless procession across the screen.

The many advantages of the invention will appear as I proceed with my specification.

In the drawings:

35 Figure 1 represents a perspective view of my improved advertising device.

Fig. 2 represents a top plan view of the device as it appears with the cover plate removed.

40 Fig. 3 represents a central, longitudinal vertical sectional view through the device, the plane of the section being indicated by the line 3, 3 of Fig. 2.

Fig. 4 represents an enlarged detail, sectional view of several of the parts shown in Fig. 3 and will be more specifically referred to later.

Fig. 5 represents a transverse, vertical, sectional view through the device, the plane 50 of the section being indicated by the line 5, 5 of Fig. 2.

Fig. 6 represents a horizontal detail, sectional view, the plane of the section being indicated by the line 6—6 of Fig. 4.

55 Fig. 7 represents a vertical, detail, sec-

tional view, the plane of the section being indicated by the line 7—7 of Fig. 2.

Fig. 8 represents a fragmentary view, in elevation of an endless band which bears the words, letters or other characters to be 60 presented in an endless procession upon the screen.

Referring now to that embodiment of my invention, illustrated in the accompanying drawings:—10 indicates a rectangular, long 65 box or casing which contains the operating mechanism of my improved advertising device. This casing is preferably made of sheet metal and has side walls 11, 11, a rear end wall 13, a bottom wall 14 and a removable top wall 15. The side walls are connected together near their front ends at the top by means of a transverse bar or plate 12^x, which acts as a brace between said walls. 12 indicates the front wall of the casing which 70 is removable. Said wall is made of glass and forms the screen upon which the words, letters, characters or the like, forming the sign, are projected.

17 indicates an upright, transverse partition wall, which divides the casing longitudinally into front and rear compartments 18 and 19. The front compartment 18 is dark and is the projecting chamber while the rear compartment 19 provides a housing for the 85 projecting apparatus and lamp and for a motor and other operating mechanism of the device.

In the rear compartment 19 about half way between its top and bottom, there are 90 fixed to the upright walls of the casing two horizontal, longitudinally extending shelves or plates 20, 21 (see Fig. 2). Said plates are separated by an intermediate space which is occupied by the projecting apparatus. Said space is bridged at the front and rear by vertically arranged plates 22, 23 which constitute supports for the lenses of the projecting device. Said plates have at 95 their ends and intermediate their top and bottom margins, horizontal, slotted flanges 22^b, 23^b, which bear upon the shelves 20, 21 and which are attached thereto by clamping screws 24, 25. This construction allows for adjustment of the position of the said plates 100 toward or from each other.

The rear plate 23 has a large opening 23^b and has fixed to it at the bottom of this opening a forwardly, extending, horizontal plate 26 (see Fig. 4) and has fixed to it at the sides 110

of said opening upright plates 26^a, 26^a (see Fig. 6), the three plates forming a frame to receive and support a lens holder or tube 27. Said lens tube is in line with the opening 23^b in the plate 23. 28, 29 indicate the familiar plano-convex condensing lenses mounted in the tube 27. The lens tube 27 is retained in its supporting frame by means of an upright plate 30, the side margins of which are attached to suitable flanges on the upright plates 26^a, 26^a, of said frame. The plate 30 has a rearwardly extending top flange 31 which engages upon and covers the top of the lens tube 27 (see Fig. 4).

15 In the plate 30 are formed a plurality of slots or openings which block out spaces through which the advertising characters are to be projected. As shown there are three of said slots, 32, 33 and 34. The top and bottom slots 32, 34, in this case are associated with stationary advertising matter. The intermediate slot 33 is associated with the traveling advertising matter. Said slots are preferably covered by means of colored strips of 25 glass or of other translucent material 32^a, 33^a and 34^a, which are held against the front face of the plate 30 in any convenient manner. As shown, said strips are held in place by means of open frame plates 32^b, 35 and 30 34^b, which are removably fixed to the upright supporting plate 30 in any suitable manner. The intermediate plate 35 is a channel bar with a longitudinal slot 35^a and forms a guide for a moving, endless opaque 35 band 36 in which are stenciled the letters, characters or other devices which provide the traveling advertising matter.

The front lens supporting plate 22 has an opening 22^b of smaller diameter than, but in 40 axial alignment with, the opening 23^b in the rear plate 23. Fixed to the front face of said plate, concentric with the opening 22^b, is a flared tube 22^x which projects at its front end through a suitable hole in the partition 45 wall 17 into the dark compartment 18.

37 indicates a tubular lens casing attached by means of a radial flange 37^a at its front end to the rear face of the plate 22, in axial alignment with the opening 22^b in said plate. 50 In the rear end of said casing is fixed a concavo-convex objective lens 38. The objective lens casing 37 is inclosed by a telescoping tube 37^x comprising two sections 37^y and 37^z. The front section 37^y is attached at 55 its front end to the plate 22 and the other section telescopes upon the first section and closes at its rear end upon the plate 30.

Back of the projecting device is placed a lamp 40 which is located in such manner as 60 to direct the rays of light given out by it, through the condensing lenses 28, 29.

Said lamp is provided with a high power electric bulb, preferably what is known as a nitrogen lamp. Said lamp is mounted as 65 shown on a bracket 39 (see Fig. 6) which

consists of a horizontal plate having depending end flanges which are adjustably attached to upright plates 39^a that are bolted to the bottom wall 14 of the casing. An opening 14^a is made in the bottom wall 70 of the casing below the lamp for the purpose of ventilation and also for the admission of the lamp cord. The top wall 15 of the casing is also provided with ventilating openings 15^a, there being a plurality of such 75 openings located above the space occupied by the lamp and by the rear end of the projecting device. The lens tube 27 and the plates connected thereto preferably have ventilating openings (see Figs. 3 and 4) to provide an upward circulation of air between the condensing lenses and toward the openings 15^a in the top wall of the casing. The rear wall 13 of the casing has an opening 13^a back of the lamp for getting at the parts 80 contained in the rear compartment 19. Said opening is closed by a hinged door 13^b.

The endless opaque band 36 which provides the traveling advertising matter is supported in the rear compartment 19 as follows. Upon the shelves 20, 21 (see Fig. 2) are mounted a plurality of flanged rollers or spools, 40, 41, 42 on the shelf 20 and 40^a, 41^a, 42^a on the shelf 21. Said rollers have bearing on suitable upright studs all 90 of which, except in the case of the roller 40, are fixed to the shelves. The rollers 40, 42 and 40^a, 42^a are placed at the four corners of the compartment 19. The rollers 41, 41^a are placed nearer the projecting device with 95 their rear peripheries tangential to the plane of the guide strip 35 that provides support for the band 36 in its passage through the projecting device. All of the rollers are in a common horizontal plane with the guide 100 strip 35 and the endless band 36 is passed about them and through the guide strip in a tortuous path as illustrated in Fig. 2. The stud on which the roller 40 has bearing is fixed to a horizontally swinging arm or 105 plate 44 which is pivoted at 45 to the shelf 20. The free end of said arm is connected by a coiled contractile spring 44^x to a fixed part of the casing in such manner as to tend to swing it forwardly, thereby taking up any 110 slack in the band and providing tension therein.

A motor and gearing as follows are provided to impart a continuous traveling movement to the band 36. An upright shaft 50 115 (see Figs. 2 and 6) is mounted between the roller 41^a and the adjacent side wall of the casing. Said shaft has bearing in plates 51^a, 51^a fixed respectively to the bottom wall of the casing and to the bottom side of the shelf 120 21. A worm gear 52 fixed to the shaft 50 meshes with a worm 53 on a horizontal shaft 54 which has bearing in upright standards 55 attached to the bottom wall of the casing. A large pulley 56 on the shaft 54 is con- 125

nected by a belt 57 to the small driving pulley of an electric motor 58. Thus the shaft 50 is driven by the motor 58, but at greatly reduced speed.

5 The shaft 50 projects upwardly through the shelf 21 and has fixed to it a toothed wheel 60. (See Fig. 7). The teeth of said wheel are adapted to engage in holes 36^y in the band 36. The holes 36^y are provided 10 throughout the entire length of the band near one edge (the top edge in this case) (see Fig. 8) and are spaced at equal distances apart. A spring controlled presser roll 61 mounted in any suitable manner on 15 the shelf 21 adjacent to the shaft 50 holds the band 36 in proper engagement with the toothed wheel 60. From the foregoing it will be apparent that when the motor 58 is operating, a continuous, feeding movement 20 in one direction (as indicated by the arrows in Fig. 2) will be imparted to the band 36.

The band 36, as has been said, is opaque and is made preferably of thin metal. Letters, characters, or other devices that are to 25 constitute the traveling or moving advertising matter, are cut out or stenciled in this band—the characters or letters and the like being thus defined by open spaces through which light may pass. This band may be 30 made of any suitable, preferably non-inflammable, material and the devices constituting the sign may be blocked out in any desirable or convenient manner, it being simply necessary that the band be so made, 35 that when light is passed through it, the characters defined upon it will be blocked out by the light so that they may be thrown on a screen as the band is passed through its guide plate 35 in front of the condensing 40 lenses.

The heretofore mentioned plates 32^b and 34^b (placed respectively above and below the traveling band) are stenciled, cut or otherwise formed to block out characters, 45 letters, or other devices, so that the light passing through said plates will throw said characters on a screen in the same way as in the case of the band. These plates being fixed, carry what has been called the stationary advertising matter, which may consist of the name of the concern advertised 50 or other matter associated with the traveling advertising matter.

The front wall 12 of the casing, which as 55 has been said is the screen upon which the sign is projected, has translucent fields 12^a, 12^a and 12^a blocked out upon it. Said fields are of such shape and are in such position as to receive the letters, devices and the like 60 projected through the stencil plates 32^b, 34^b and through the traveling band 36. Said fields are preferably made by sand blasting or frosting the glass while the remainder of the glass is rendered opaque by black 65 paint or otherwise.

The operation of the apparatus is apparent from the foregoing description. As the band 36 travels through its guide plate 35, the light rays from the lamp are condensed and projected through the several 70 colored transparent strips fixed to the plate 30 and through the stencil plates 32^b, 34^b and through the band 36. The color plates soften the intense glare or ray from the lamp before it passes through the stencil 75 openings. The light rays from the lamp after they have passed through the stencil plates and the band, pass through the objective lens 38 and are thereby projected through the dark compartment 18 and upon 80 the several associated fields on the front wall 12 of the casing. The dark compartment prevents diffusion of the projected light rays and adds to the brilliancy of the sign 85 thrown on the screen.

By reason of the longitudinal adjustment of the plate 22, which carries the objective lens, a proper focus of the matter to be projected upon the screen may be attained, the tube 37^x telescoping upon itself and entirely 90 inclosing the projected light rays between the condenser and objective lenses, no matter what the distance between them may be.

When the device is in operation there is 95 presented upon the various fields of the front wall of the casing, a unique and attractive display. The name of the company or other advertising matter appears stationary and immovable upon the screen. The advantages of the use of the advertised device or of the service rendered by the company advertised, is also presented upon said screen in the form of moving letters or characters defining words which seem to appear from nothing at one end of the field and dissolve or fade away into nothing at the other end of said field, new words always appearing in an endless procession to take the place of the words fading out.

100 My invention possesses many advantages 110 besides the one advantage which arises by reason of its attracting the attention of the passerby. It is made of non-inflammable material and is otherwise constructed to meet various insurance ordinances regarding 115 display devices. It is light in weight and portable and may be readily used in the display window of a shop or store. It operates to advantage either in daylight or at night as the light rays are projected 120 upon the screen through the inclosed dark compartment, thus conserving the light rays. The stencils may be easily changed as also the band and the screen may also be changed to correspond. Any suitable switch (not 125 shown) may be used to control both the motor and the lamp, so that the lamp will be turned on or off at the same time that the motor is started or stopped.

130 While in describing my invention I have

referred to certain details of mechanical construction and arrangement of parts, I do not wish to be limited thereto except as may be pointed out in the appended claims.

5 I claim as my invention:

1. A device of the kind described, comprising a casing having a front wall providing a screen, a projecting apparatus and lamp located in said casing at a distance

10 from said front wall, an endless band having letters, characters and the like blocked out upon it, means for supporting and guiding said band through said projecting apparatus, means for imparting continuous move-

15 ment in one direction to said band, a fixed plate or plates having letters, characters and the like blocked out upon them and located in said projecting apparatus above or below said traveling band and said screen being provided with translucent fields associated 40

20 with and adapted to receive the letters, characters and the like thrown by said projecting apparatus from said traveling band and from said fixed plates in the projecting ap- 45

25 paratus.

2. A device of the kind described comprising a casing having a front wall providing a screen, a projecting apparatus and lamp located in said casing at a distance

30 from said front wall, an endless band having letters, characters and the like stenciled or cut in it, means for supporting and guiding said band through said projecting apparatus, means for imparting continuous move- 50

35 ment in one direction to said band, a fixed

plate or plates having letters, characters and the like stenciled or cut in them and located in said projecting apparatus above or below said traveling band and said screen being provided with translucent fields associated 40

with and adapted to receive the letters, characters and the like thrown by said projecting apparatus from said traveling band and from said fixed plates in the projecting ap- 45

paratus.

3. In a device of the kind described in combination with a casing and a projecting apparatus located therein, shelves fixed in said casing at each side of said projecting apparatus, means whereby said projecting apparatus is adjustably supported on said shelves, an endless band, a slotted guide plate extending through said projecting ap- 55

paratus which constitutes a guide for said band, a plurality of rollers mounted on said shelves which together with said guide plate provide support for said band in a tortuous path, one of said rollers having a spring controlled bearing movable in a direction to put tension in said band, and means for im- 60

parting movement to said band.

In testimony that I claim the foregoing as my invention I affix my signature in the presence of two witnesses, this 15th day of June A. D. 1916.

CLYDE ERSKINE.
